UNITED STATES PATENT OFFICE.

BERNARD R. DUTCHER, OF NEW YORK, N. Y., ASSIGNEE TO GRAHAM-CHISHOLM COMPANY, OF NEW YORK, N. Y., A CORPORATION OF NEW YORK.

LOOSE-LEAF BINDER AND SUPPORT THEREFOR.

Application filed January 21, 1921. Serial No. 438,934.

To all whom it may concern:

Be it known that I, BERNARD R. DUTCHER, a citizen of the United States, residing in New York, in the county of New York and State of New York, have invented certain new and useful Improvements in Loose-Leaf Binders and Supports Therefor, of which the following is a specification.

This invention relates to improvements in loose-leaf binders and to supports cooperating with the loose-leaves and with the binder for aiding in their manipulation.

My support is especially designed for use with a temporary binder or loose-leaf holder or book, and I have shown my device in use with two forms of the binder; but the improvements both in the cover and the supports are capable of embodiment and are desirable for use with other forms of temporary binders and in other relations where it is desirable to facilitate the handling of loose-sheets.

The main objects of the invention are:

First, to provide an improved support or device which facilitates the use of temporary binders or loose sheet holders and particularly those in accounting systems.

Second, to provide a loose-leaf binder which facilitates the handling or manipulation of loose record sheets when used with the above mentioned support.

Third, to provide an improved device which facilitates the manipulation and handling of temporary binders and the insertion and removal of sheets therefrom.

Fourth, to provide a single practical, durable, easily manufactured support of the kind mentioned above.

Other objects of the invention will appear as the description proceeds; and while herein minute details of the invention are described, the invention is not limited to these, since many and various changes may be made without departing from the scope of the invention as claimed.

In the accompanying drawing, showing by way of example, two of many possible embodiments of the invention,

Figure 1 is a perspective view of a structure embodying the features of my invention;

Fig. 2 is a view similar to Fig. 1, but with a binder therein;

Fig. 3 is a perspective view of said struc-

ture with separated portions of a binder 55 therein;

Fig. 4 is a side elevation showing a detail of movable guide strips comprised in said structure, and the binder in position for removal; and 60

Figs. 5, 6 and 7, are plan views of modified forms of binder cover boards, with a clamping bar connected thereto.

My improved loose-leaf support or tray is adapted for use with a loose-leaf book 65 binder 5 (Fig. 2), comprising a pack of leaves 7, each having near its inner edge 8, a pair of perforations 11 equally spaced from said inner edge 8, and equally spaced from the adjacent ends of the sheet. 70

Said book binder also comprises a pair of clamping bars 12, adapted to be placed one on each side of said pack of leaves at said inner edges and each provided with a key hole 13 at one end and with locking 75 openings registering with the perforations of the sheets 11. A pair of posts 16 pass through said perforations 11 and are locked in said locking holes by suitable locking means comprising a squared key-receiving arbor in said key hole 13. Binding or cover boards 18 are hinged to said clamping bars 12 and are adapted to cover said pack and project a slight distance at the top and bottom edges of said leaves, except at the 85 elongated recesses 19, the edge portions 20 of the recesses 19 being near or approximately flush with the edges of the leaves.

The support itself comprises a pair of side bars or members 25, and front and rear 90 straps 26 having their ends downturned over the outer edges of the side bars and secured thereto, there being cooperating straps 26' under the straps 26 having downturned ends engaging the inner edges of the side bars 95 and secured thereto. A U-shaped member or yoke 27 secured transversely on said bars has upturned guide strips 28 for engaging in said recesses 19 and against the end edges 100 of said leaves.

Suitable protecting domes 30 of metal, rubber or the like are provided under and for supporting said bars for preventing the scratching of the desks, tables or the like on which the support may rest. Or, suitable 105 legs or other support may be provided for supporting the device from the floor.

A pair of supporting strips 34 are secured

on the forward end of said side bars and are bent to form a pair of upright stops 35 about midway between the front and rear of said bars 25 and adapted for engaging the forward edges of the clamping bars 12 when the book-binder 5 is held by the yoke member 27. Said strips 34 are formed with forwardly and downwardly steeply inclined forward supporting stops 37, extending from the upper end of said stops 35 and formed with a forward turn or loop 38 joining upwardly and less steeply inclined forward supporting strips 40 (Fig. 2) which extend from said stops 35 to the upper end of the front-end-supports 41 secured on the forward ends of said bars 25; the purpose of the turns or loops 38 being to receive the rounded portions 12' of the edges of the clamping bars 12, which extend beyond the edges of the leaves 7 of the book-binder. About midway of said strips 40 is disposed a U-shaped member 41 having its yoke loosely secured as by a loose connection 42 formed by a bolt 43 fixed to the strip 40 and loosely passed through perforations on said yoke 41 which is held in place by nuts 44 below said strips 40, the ends of said yoke 41 being upturned to form movable guide strips 45 adapted when the cover board 18 (Fig. 3) is resting on said forward guide strips 40, to engage in said recess 19 and substantially against the leaves 7, thereby to position the loose-leaves away from the edge of the cover board as the leaves are applied. Said guide strips 45 because of the loose connection 42 are movable outwardly, away from the stops 37 for the easy insertion and removal of the cover boards and the removal of the book. The binder posts 16 are locked before the loose-leaf book is removed from the yoke 41.

The operation of the device is very simple.

The bound and locked loose-leaf book or binder is placed on the support with its rear cover resting upon the side bars 25 (Fig. 2), with the guide strips 28 engaging in the recesses 19 and substantially against the edges 20 and the edges of the leaves, the forward edges of the leaves or sheets being exposed and their inner edges engaging against the stops 35, the key holes 13 of the clamping bars of the binders being fully exposed.

A key is then inserted into the key holes and the posts 16 are unlocked, whereupon the posts and the forward cover boards 18 are removed, and the forward cover board placed upon the supporting strips 40, as in Fig. 3.

The leaves or sheets are then taken up one by one or in groups and deposited on the forward cover board 18 with their inner edges against the stops 37, the guide strips 45 positioning the leaves on the cover board or each other.

After all of the sheets have been placed

in proper order on the forward part of the support, the rear cover board is placed thereon, the posts replaced and locked.

After the posts are thus locked in place, both side edges of the book are exposed thus permitting the hands to grasp the edges of the book, the loose joint 44 permitting the cover boards and leaves to be first moved away from contact with the strips 37 and out of engagement with the turns or loops 75 38.

Obviously, the operations above described and other features of the invention will be found useful in many operations other than those relating to accounting. 80

In the form of cover board shown in Fig. 5, the recesses 19, and edge portions 20 thereof are reinforced by metal or suitable material.

In the form of cover board shown in Fig. 6, the recesses 19' and the long edges 20' thereof are made much longer than the width of guide strips 45; and the yoke 41 is secured fast to the lower face of said strips 40, said strips 45 being adapted when the cover board 18 (Fig. 4) is resting on said forward guide strips 40 to engage loosely in said recesses 19'. Said guide strips 45, because of the loose engagement in the recesses 19', permit the cover boards to be removed outwardly 95 away from the strips 37 for the easy insertion and removal of the cover boards and the removal of the book.

The form of cover board shown in Fig. 7 is provided with rectangular apertures 46, instead of recesses for receiving the guide-strips 28 or 45, as the case may be, these apertures preferably being reinforced by metal or suitable material. 100

Obviously, in relation to the modified form of cover board, Fig. 6, the guide strips of either a fixedly mounted yoke 41 or a loosely mounted yoke 41 could loosely engage in the long recesses 19', thus permitting great movement of the binder away from 110 the stops 37.

Having thus described my invention, I claim:

1. A loose-leaf book comprising a cover board provided with guide-receiving guide means in an edge thereof. 115

2. In combination, a support; upstanding guides at the sides of the support; and a binder having edge guide means engaging said guides. 120

3. In combination, a support; upstanding guides at the sides of the support; and a binder having edge means loosely receiving said guides.

4. In combination, a support; upstanding guide strips mounted at the sides of said support; and a binder having edge recesses loosely receiving said strips. 125

5. In combination, a support; upstanding guide strips loosely mounted at the sides of 130

said support; and a binder having edge recesses loosely receiving said strips.

6. In combination, a support; a cover board provided with an edge recess and adapted to rest on said support; and guide strips on said support and disposed in said recess.

7. In combination, a horizontal rear support; upright rear stops; downwardly and forwardly inclined forward stops forward of said rear stops; upwardly and forwardly inclined forward supporting strips extending from the lower ends of the forward stops; a book-binder including cover boards provided with edge recesses and adapted to rest on said forward supporting strips; and guide strips slightly spaced from and about midway of said forward strips and loosely mounted thereon and loosely disposed in said recesses to position the leaves of the book binder.

8. In combination, a horizontal rear support; upright rear stops; downwardly and forwardly inclined forward stops forward of said rear stops; upwardly and forwardly inclined forward supporting strips extending from the lower ends of the forward stops; covers provided with edge recesses and adapted to rest on said forward supporting strips with their inner edge against said forward stops; leaves on said covers; and guide strips slightly spaced from and about midway of said forward strips and mounted thereon and disposed in said recesses to position said leaves.

9. In combination, a horizontal rear support; upright guide strips at the sides thereof; an upwardly and forwardly inclined forward support; upright guide stops separating said supports; a book comprising a pack of leaves, clamping bars adapted to be placed on each side of said pack of leaves at their inner edges, or to be separated and rested on said supports and against said guide stops; binding covers carried by said clamping bars adapted to cover said leaves and to be separated with the same and to rest on said supports with the leaves thereon, and provided with end-edge recesses having their inner edges substantially flush with the end edges of the leaves; and guide strips secured to said forward support and adapted to be received by said recesses when the covers are resting on said supporting strips and bars, and the inner edges of the covers and leaves are resting against said stops.

10. In combination, parallel horizontal supporting bars; upright side guide-strips near the rear thereof; upright rear stops about midway of the bars; downwardly and forwardly inclined forward supporting stops extending from the upper end of said rear stops; upwardly and forwardly inclined forward supporting strips extending from the lower end of the forward stops;

guide strips slightly offset from and about midway of said forward strips; a pack of leaves; clamping bars having intermediate openings and adapted to be placed on each side of said pack of leaves at their inner edges or the clamping bars to be separated and rested on said horizontal supporting bars and supporting strips and against said rear and forward stops; binding cover boards hinged to said bars and adapted to cover said pack and project at the top and bottom edges of said leaves and provided with elongated end-edge recesses having their inner edges substantially flush with the end edges of the loose leaves and adapted to receive said guide strips and bars; loose leaves each having at the inner edge a plurality of perforations registering with said openings of the clamping bars; removable posts adapted to be passed through the openings of the clamping bars and the perforations of the leaves; and means for locking the posts in said openings.

11. A loose-leaf book comprising a cover board having an elongated guide-receiving recess in an edge thereof.

12. A loose-leaf book comprising, removable cover boards, each having an elongated recess in an edge thereof; and a pack of leaves between said boards having an edge substantially flush with the inner edge of said recess.

13. A loose-leaf book comprising, removable cover boards, each having an elongated recess in both end-edges; and a pack of leaves therebetween, each having its end edges substantially flush with the inner edge of said recesses.

14. In combination, side bars; straps for connecting the side bars and spacing them apart; a yoke member secured transversely to the side bars and provided with upturned guide strips; forwardly extending guide stops having supports secured to the side bars; forwardly extending supporting strips having supports secured to the side bars; a transverse yoke on the supporting strips provided with upturned guide strips; and a book binder; the book binder normally being in position on the side bars between the guide strips of the first mentioned yoke member and the supports of said guide stops, and being receivable against said guide stops and between the guide strips of the second mentioned yoke member and supported by said supporting strips.

15. In combination, side bars; straps for connecting the side bars and spacing them apart; a yoke member secured transversely to the side bars and provided with upturned guide strips; forwardly extending guide stops having supports secured to the side bars; forwardly extending supporting strips having supports secured to the side bars; a transverse yoke on the supporting strips

provided with upturned guide strips; and a book-binder comprising a pack of leaves and cover boards therefor, the end edges of the cover boards extending beyond the edges of said pack of leaves and being provided with recesses therein; the book-binder normally being in position on the side bars between the guide strips of the first mentioned yoke member and against the supports of said guide stops, the guide strips of said yoke member engaging in the recesses of the cover boards; and the book-binder being receivable against said guide stops and between the guide strips of the second mentioned yoke member and supported by said supporting strips, the guide strips of the second mentioned yoke member engaging in the recess of the cover boards.

16. In combination, side bars; straps for connecting the side bars and spacing them apart; a yoke member secured transversely to the side bars and provided with upturned guide strips; forwardly extending guide stops having supports secured to the side bars; forwardly extending supporting strips having supports secured to the side bars; the guide stops and the supporting strips being connected by loops; a transverse yoke

30 on the supporting strips provided with upturned guide strips; and a book-binder comprising a pack of leaves, cover boards therefor, and clamping bars; the end edges of the cover boards extending beyond the edges of said pack of leaves and being provided with recesses therein, and the clamping bars having longitudinal edges extending beyond the edges of the pack of leaves; the book-binder normally being in position on the side bars between the guide strips of the first mentioned yoke member and against 40 the supports of said guide stops, the guide strips of said yoke member engaging in the recesses of the cover boards; and the book-binder being receivable against said guide stops and between the guide strips of the second mentioned yoke member and supported by said supporting strips, the guide strips of the second mentioned yoke member engaging in the recesses of the cover boards, and the extending edge of one of 45 said clamping bars being received in said loop connections of the guide stops and supporting strips.

BERNARD R. DUTCHER.
